C. L. HOOPES.

SUBMERGED PILE AND MEANS FOR CONSTRUCTING THE SAME.

APPLICATION FILED FEB. 12, 1919.

1,360,986.

Patented Nov. 30, 1920.

UNITED STATES PATENT OFFICE.

CHARLES LEWIS HOOPES, OF SAN DIEGO, CALIFORNIA.

SUBMERGED PILE AND MEANS FOR CONSTRUCTING THE SAME.

1,360,986.

Specification of Letters Patent. Patented Nov. 30, 1920.

Application filed February 12, 1919. Serial No. 276,458.

To all whom it may concern:

Be it known that I, CHARLES LEWIS HOOPES, a citizen of the United States, residing at San Diego, in the county of San Diego and State of California, have invented certain new and useful Improvements in Submerged Piles and Means for Constructing the Same, of which the following is a specification.

10 My invention relates to a pile structure and more particularly to a means for covering wooden or other similar piles with concrete to prevent their deterioration in the water by teredo and the like or for a pile 15 structure formed by the use of an ordinary pile used as a guide pile for placing and properly positioning the constructed pile and then removing the same and filling the interior with concrete and the objects of my 20 invention are first, to provide a pile structure of this class in which a pile is driven as a core and a plurality of annular reinforced concrete form members are positioned around said pile and the space between the 25 pile and said concrete form member filled, second, to provide a pile structure of this class in which an ordinary pile is driven and a plurality of annular reinforced concrete form members positioned around said pile 30 then said pile is removed and the interior filled with concrete, third, to provide means for covering piles already driven with a concrete layer for preserving the submerged portion of said pile, fourth, to provide a 35 means for covering the submerged portion of a pile with cement while said pile is submerged and in which the mold in which the concrete is poured is left in position and forms a part of the concrete covering, fifth, 40 to provide a pile structure of this class in which a plurality of annular reinforced concrete members with interlocking edges are secured together forming a pile of the pedestal pile form which may be either left 45 hollow or filled internally with concrete after the same is sunk to position, and sixth, to provide a pile structure of this class which is very simple and economical of construction, durable, easy to install and 50 which will not readily deteriorate or get out of order.

With these and other objects in view as will appear hereinafter, my invention consists of certain novel features of construction, combination and arrangement of parts 55 and portions as will be hereinafter de-

scribed in detail and particularly set forth in the appended claims reference being had to the accompanying drawings and to the characters of reference thereon which form 60 a part of this application in which:

Figure 1 is a longitudinal sectional view of one of my pile structures showing the wooden core portion in position and showing the concrete portion partially embedded in 65 the earth by the use of a jet; Fig. 2 is a sectional view along the line 2-2 of Fig. 1; Fig. 3 is a longitudinal sectional view of my structure as applied to a pile partially destroyed by teredo or the like; Fig. 4 70 is a detailed fragmentary sectional view of the lower end of a pedestal pile structure in a slightly modified form from that of Figs. 1, 2 and 3 and Fig. 5 is a top view 75 thereof.

Similar characters of reference refer to similar parts and portions throughout the several views of the drawings.

The ordinary pile core portion 1, annular monolithic mold member 2, cement body 3, 80 and jet 4 constitute the principal parts and portions of my pile structure.

The pile 1 is an ordinary pile usually wooden which is driven or jetted into the ground in the position desired and over the top of this pile and passes down and over the same are a plurality of annular monolithic concrete members 2 provided with interlocking edges 2^a so that these annular members interlock with each other thus 90 forming a concrete shell spaced apart from the outer surface of the pile which serves as a mold. Each of these members 2 are provided with reinforcing bars 2^b and 2^c and the lugs 2^d adapted for the rods 2^e and 95 with other lugs 2^f which are threaded to receive the threaded ends of the rods 2^e for securing the separate members 2 together. The lower end of this shell is jetted into the earth some distance by means of the jet 4 100 thus forming a mold from some distance below the surface of the earth to above the high water line and between the pile 1 and the shell formed by the member 2 concrete is poured filling said spaces thus forming 105 a pile the submerged portion of which consists of a wooden or other pile as a core with concrete poured around the same and an outer surface consisting of a plurality of interlocked monolithic reinforced annular 110 members.

In the form of structure shown in Figs. 4

and 5 there is shown a pedestal pile which is constructed in a similar manner except that the lower end is provided with an enlarged tapering concrete member 5 which is 5 provided with a sharp edge 5^a adapting it to enter the earth when the ground is taken out from the inside of the member 5. This member tapers at 5^b and on its upper edge it is provided with an extended portion 5^c 10 which interlocks with the annular member 2. This structure is constructed by first driving a plurality of guide piles 6. In this form of construction the joints between the members 2 and the members 2 and 5 are 15 made water tight by covering the edge surfaces with tar, oakum or other water tight substance and these members 2 and 5 are secured together by means of rods 2^e which extend from one section to the other which 20 is secured in one of said members and the one end of which is threaded to screw into a lug 2^h which is embedded in the concrete in an adjacent member. It will be noted that these members 2 may be molded in any 25 position desired and transported to the place of use or they may be molded in position above the surface of the water and lowered into position and the different sections secured together until the lower section 5 30 reaches the earth and is supported thereby after which it may be jetted some distance forming a coffer dam after which the inside may be cleaned or dug out and the same sunk to any position desired. It will be noted 35 that these members 2 and 5 are each provided with suitable reinforcements to provide the proper strength for said members as hereinbefore described.

Though I have shown and described a particular construction, and certain modifications thereof I do not wish to be limited to this particular construction, nor to the modifications thereof nor to the particular means for providing forms for producing 45 the pile but desire to include in the purview of my invention the construction, combination and arrangement substantially as set forth in the appended claims.

It is obvious that with this construction, 50 there is provided a pile structure and means for forming a pile structure in the water in submerged position in which a concrete pile may be molded in position in the water or a pile driven as a core and the same covered 55 with a concrete covering or a pile already

driven and partially deteriorated may be reconstructed with a concrete covering and reinforcement, that the members 2 provide a shell mold into which the concrete may be poured and permitted to set which remain 60 in position as an additional outer covering for the pile, that the structure and means for building the structure is simple and economical of construction, durable, easy to install, easy to operate and that both the pile 65 structure and means for constructing the pile are durable and will not readily deteriorate or get out of order.

Having thus described my invention what I claim as new and desire to secure by Letters Patent is:

1. A structure of the class described, including a vertical pile driven into the earth, forming a core, a plurality of annular, monolithic, reinforced, plastic members positioned 75 one above the other and provided with inner and outer extended portions whereby they are interlocked with each other, a rod secured to one of said members on the inner surface thereof, a lug secured to another of 80 said members on the inner surface thereof adapted to receive said rod for securing said members rigidly together and concrete filling the space between said core member and said monolithic reinforced plastic members. 85

2. An apparatus of the class described, including a pile member driven into the earth, forming a core, a casing surrounding said core and spaced apart therefrom, consisting of a plurality of annular, monolithic, reinforced, plastic sections provided with annular inner extended flanges on their one end and with annular outer extended flanges on their opposite ends so that when they are placed end to end they interlock with each 95 other, a plurality of supports secured near one end of each of said sections and extending inwardly in said sections, rods mounted in said supports, other supports in said sections provided with threaded ends adapted 100 for the threaded ends of the rods on an adjacent section whereby said sections are rigidly secured together and concrete filling the space between said driven pile and said casing.

In testimony whereof, I have hereunto set my hand at San Diego, California, this 1st day of February, 1919.

CHARLES LEWIS HOOPES.
